DESIGN.

M. MELLINGER.
CEILING DECORATION.

No. 17,746.

Patented Sept. 27, 1887.

UNITED STATES PATENT OFFICE.

MICHEL MELLINGER, OF NEW YORK, N. Y., ASSIGNOR TO WARREN, LANGE & CO., OF SAME PLACE.

DESIGN FOR CEILING-DECORATION.

SPECIFICATION forming part of Design No. 17,746, dated September 27, 1887.

Application filed August 22, 1887. Serial No. 247,618. Term of patent 3½ years.

To all whom it may concern:

Be it known that I, MICHEL MELLINGER, a citizen of France, residing in New York city, in the county and State of New York, have invented a new and original Design for Ceiling-Decorations, of which the following is a specification, reference being had to the accompanying photograph, which forms a part of the same.

10 The invention relates to a design shown on surfaces, such as paper for ceiling-decorations or similar articles; and it consists in the novel configuration and grouping of figures herein specifically shown and claimed.

15 The accompanying photograph is a face view of ceiling-paper showing my new design. My design consists of a body part, A, and a border, B.

20 The main feature of the body A is the sun-bursts, which are circular in general form and have a solid center, from which radiate sharp needle-like shafts or rays on every side. These

sun-bursts are scattered upon a ground ornamented with a fine continuous lace-work.

25 The border B has an outer and inner edge or margin of an ornamental character. The middle portion of the border is covered with a prominent lace-work, under which appear the radiating needle-like shafts of sun-bursts, shown only in part.

30 What I claim as new, and desire to secure by Letters Patent, is—

1. The design for ceiling-paper, consisting of the body A, substantially as shown.
2. The design for ceiling-paper, consisting 35 of the border B, substantially as shown.
3. The design for ceiling-paper, consisting of the body A and border B, substantially as shown.

MICHEL MELLINGER.
